UNITED STATES PATENT OFFICE.

JAMES M. BONNER, JR., OF LOS ANGELES, CALIFORNIA.

DESIGN FOR A LAVATORY.

Application filed December 29, 1928. Serial No. 29,442. Term of patent 7 years.

To all whom it may concern:

Be it known that I, JAMES M. BONNER, JR., a citizen of the United States, residing at Walnut Park, Los Angeles, in the county of Los Angeles and State of California, have invented a new, original, and ornamental Design for Lavatory, of which the following is a specification, reference being had to the accompanying drawing forming a part hereof.

Figure 1 is a front elevation of a lavatory showing my new design;

Figure 2 is a top plan view thereof.

I claim:

The ornamental design for a lavatory substantially as shown.

Signed at Los Angeles, Calif., this 20th day of December, 1928.

JAMES M. BONNER, JR.
